NECKTIE

Leonard W. Beck, Kettering, Ohio, assignor of a fractional part interest to Walter Becker, Kettering, Ohio

Filed July 20, 1972, Ser. No. 273,625

Term of patent 14 years

Int. Cl. D2—05

U.S. Cl. D2—354

FIG. 1 is a front perspective view of a necktie showing my new design;

FIG. 2 is a rear perspective view thereof;

FIG. 3 is a front elevational view;

FIG. 4 is a rear elevational view;

FIG. 5 is a side elevational view;

FIG. 6 is a top plan view;

FIG. 7 is a bottom plan view; and

FIG. 8 is a cross sectional view on the line 8—8 of FIG. 3.

I claim:

The ornamental design for the necktie, as shown.
